ROTARY COMPRESSOR

Sven Malke, Milwaukee, Wis., assignor to A. O. Smith Corporation, Milwaukee, Wis., a corporation of New York

Application June 24, 1944, Serial No. 541,915

14 Claims. (Cl. 230—177)

1

The invention relates to a rotary compressor and more particularly to a compressor that may be employed with refrigeration units and the like.

One object of the present invention is to provide a rotary compressor in which lubrication is simplified and friction and vibration is substantially eliminated.

Another object is to provide a lighter weight rotary compressor unit that is readily fabricated and assembled.

A further object is to provide a rotary compressor of improved volumetric efficiency per unit delivery of fluid for piston displacement.

Other objects and advantages of the invention will be set forth in the following description of an embodiment of the invention illustrated in the accompanying drawings.

In the drawings:

Figure 1 is a longitudinal sectional view of the rotary compressor of the invention designed for refrigeration units;

Figure 2 is a section taken on line 2—2 of Figure 1 looking in the direction of the arrows;

Figure 3 is a section taken on line 3—3 of Figure 1 looking from the left and showing in particular the left hand collector end ring with a part of the ring broken away;

Figure 4 is a section taken on line 4—4 of Figure 1 showing a top plan view of one of the cylinders and

Figure 5 is a section similar to Figure 1 showing a modified construction utilizing the principles of the invention.

The rotary compressor of the invention comprises in general an outer casing having a cupped shaped cylindrical member 1 sealed and closed at its open end by a relatively flat member 2 secured thereto in any suitable way, as by bolting the members together.

A shaft 3 is journaled in the opposite ends of the casing, axially thereof, and extends through the head 2 for connection to a motor shaft or the like.

The cylinders 4 and 5 are secured together at right angles to each other by bolts 6, the shaft 3 passing transversely therethrough offset from the center of each cylinder. The cylinders are mounted for rotation on end bearings 7 extending inwardly from the ends of the casing, the axis of rotation of the cylinders being offset from the axis of the shaft 3. The cylinders 4 and 5 are closed at their outer ends by removable caps 8 and each cylinder has its outer wall flanged to provide a flat circular plate 9 integral therewith and lying in a plane at right angles to the axis of rotation of the cylinder.

The pistons 10 are reciprocably disposed within each of the cylinders 4 and 5 and the central bore of each piston houses a cylindrical eccentric 11 which is formed integral with the shaft 3 and

2

is preferably disposed on the shaft at 180° to the other eccentric. The rotation of the eccentrics by shaft 3 reciprocates the pistons 10 within their respective cylinders 4 and 5.

5 The arrangement whereby the axes of eccentrics 11 are offset from the axis of shaft 3 and the axis of rotation of cylinders 4 and 5 is also offset from that of the shaft, effects rotation of cylinders 4 and 5 by the eccentrics at one-half 10 the speed of the shaft 3, and also the reciprocation of pistons 10 in their respective cylinders.

The cylinders 4 and 5 are provided with inlet ports 12 at their inner ends for the intake of fluid, and the diagonal ports 13 at their outer ends for the discharge of fluid. The inlet ports 12 constitute recesses in the walls of the cylinders by-passing the pistons 10 when the latter are at the extreme inward positions of their respective strokes.

20 The ports 12 communicate with the central fluid intake chamber around the shaft 3 and extend in registered relation on a circumferential line whereby they are closed by the piston 10 after the commencement of the reversal of the piston stroke and open to receive fluid when the piston of the respective cylinder is in the extreme retracted position.

The ports 13 are disposed only in the outer wall of each cylinder 4 and 5 and extend diagonally through the cylinder wall to the outermost area of the piston displacement space or cylinder chamber 14.

30 The closure member 2 of the compressor casing which is shown at the right side of Figure 1 is formed with a ring shaped collector shoe 15 adapted to engage the plate 9 formed integral with the wall of the adjacent cylinder 4.

The collector shoe of member 2 is provided 35 with a passage 16 the inner end of which alternately registers with one of the diagonal ports 13 extending through the side wall of cylinder 4 and the outer portion of which is fabricated for receiving any suitable connection to carry off the compressed fluid.

40 At the left side of Figure 1, the collector shoe 17 there shown, which is similar to shoe 15, is mounted and held against rotation on casing member 1 by a plurality of studs 18 but is permitted limited axial movement. A plurality of 45 springs 19 are seated within suitable apertures in collector shoe 17 and bear against the casing wall. This gives a floating support to the entire compressor assembly in service and eliminates tolerance problems, since the springs 19 serve to bias the collector shoe 17 against plate 9 formed integral with cylinder 5 and to bias all of the moving parts to the right to also maintain a tight seal between cylinder 4 and collector shoe 15.

50 The springs 19 thereby compensate for manufac- 55

60 The springs 19 thereby compensate for manufac-

turing tolerances in the construction of the compressor.

A passage 20 is provided through the outer portion of the collector shoe 17 and through the casting member 1 to carry off discharge fluid from diagonal ports 13 in the wall of cylinder 5 when each port registers with passage 20 in the course of rotation of the cylinder. The passage 20 is connected by a short bellows coupling 21 to the outlet 22 for the pump.

The shaft 3 may have a longitudinal port 23 and suitable transverse ports 24 communicating therewith for the purpose of distributing lubricants to the desired bearing surfaces.

The actual operation of the compressor of the invention may be confined to describing the operation of cylinder 4 and its associated parts since the description with respect to cylinder 5 would be similar.

Referring now to Figure 1, the piston 10 is shown at the end of the stroke. At this time the fluid enters through inlet ports 12 into chamber 14 of cylinder 4. Upon entry of fluid into chamber 14 piston 10 begins to advance on its reverse stroke by action of eccentric 11 rotated by shaft 3.

The collector ring 15 closes the outlet port 13 during the time when the piston 10 is in its compression stroke and is being advanced in chamber 14 toward the head of the cylinder by eccentric 11 to compress the fluid contained within the chamber and until the piston 10 is substantially in the extreme outward stroke position.

In the final stages of compression of the fluid the rotation of cylinder 4 registers port 13 with passage 16 in collector ring 15 and the compressed fluid is discharged through the registering port and passage by the final stroke movement of the piston in chamber 14. The cycle of inflow of fluid into chamber 14 and compression of the same in the manner described is then commenced again to provide for a continuous pumping of compressed fluid.

While at one end of cylinder 4 the piston 10 is compressing and discharging fluid through port 13, at the other end the piston 10 is being retracted and effects the entrance of fluid through ports 12 at that end.

Since cylinder 5 is preferably disposed at a 90° angle to cylinder 4 there are four discharges of compressed fluid for each complete revolution of the cylinders, and for every two revolutions of the shaft.

In the embodiment of Figs. 1 to 4, the outer casing need not be sealed and can be eliminated. The inlet of fluid is provided through conduit 25 and passage 26 in the end bearing 1 to ports 12 radially spaced around each cylinder.

In the modified construction illustrated in Fig. 5, there is no outer casing and air enters the cylinders directly through the ports 12 in the cylinder walls from the outside. In this construction the ports 13' may also be used for inlet of fluid to the cylinders by uncovering the same during the intake stroke of the pistons. This is readily accomplished by slotting the collector ring 15' in the sector representing the intake cycle of the respective cylinders. In Fig. 5 collector ring 15' is sectioned at the top where the discharge cycle is shown but at the bottom of the figure where the inlet is shown the ring 15' is not sectioned but is in full, representing a slot therein through which air may pass to port 13'.

The invention provides a rotary compressor in which lubrication is held at a minimum since

friction is substantially eliminated by the particular type of construction employed.

The sealing surface for the fluid passages is at the end of the unit where there is no chance for binding. The floating support of the assembled parts of the unit compensates for tolerances and clearances and maintains the required seals.

Various embodiments of the invention may be employed within the scope of the accompanying claims.

I claim:

1. A rotary compressor comprising a cylinder rotatably disposed on a fixed bearing to rotate on a transverse axis, reciprocating means for compressing fluid in said cylinder, a transverse shaft supporting said means and extending through said bearing to rotate said means on an axis offset from the transverse axis of the cylinder to effect rotation of the latter and reciprocation of said means therein, passages through a side wall of said cylinder to supply fluid thereto during a portion of the rotation cycle of the cylinder and to discharge compressed fluid from the cylinder during another portion of the rotation cycle of the cylinder, and valve means operable in response to the rotation of said cylinder to open and close said passages in synchronism with the reciprocation of said first named means.

2. A compressor comprising a cylinder rotatably disposed on a fixed bearing to rotate on a transverse axis, a reciprocating piston for compressing fluid in said cylinder, a transverse shaft supporting said piston and extending through said bearing to rotate the piston on an axis offset from the transverse axis of rotation of the cylinder to effect rotation of the latter and reciprocation of the piston therein, a passage through the side wall of said cylinder to supply fluid thereto and discharge compressed fluid therefrom, and a collector plate disposed against the side wall of said cylinder to close the said passage during the compression cycle and to open said passage for supply and discharge of fluid therethrough.

3. A compressor comprising a cylinder rotatably disposed on a transverse axis, reciprocating means for compressing fluid in said cylinder, a passage through the side wall of said cylinder to discharge compressed fluid therefrom, a collector plate disposed in said compressor to close said passage during the compression cycle, and floating support means to support said collector plate and bias the same against said cylinder wall to substantially eliminate clearance problems in the assembled parts.

4. A compressor comprising a cylinder rotatably disposed on a transverse axis, reciprocating means for compressing fluid in said cylinder, a passage through the side wall of said cylinder to discharge compressed fluid therefrom, a collector plate disposed in said compressor to close said passage during the compression cycle, a passage in said collector plate registering with the passage in said cylinder during the discharge cycle to provide means to carry off the discharged compressed fluid, and floating support means to support said collector plate and bias the same against said cylinder wall to substantially eliminate clearance problems in the assembled parts.

5. A rotary compressor comprising a casing having a cupped shaped member closed at the open end by a substantially flat closure member, a shaft journaled for rotation in said casing, eccentrics disposed on said shaft at substantially 180° to each other, a pair of cylinders mounted

in said casing eccentric to said shaft and secured together at substantially right angles to each other, pistons provided in each of said cylinders and disposed on the shaft for reciprocation by said eccentrics, passages disposed in the wall of each of said cylinders for inlet and outlet of fluid, and a collector plate disposed at each end of the casing to close the discharge passage in each said cylinder during the compression cycle thereof and to open the same for discharge thereafter.

6. A rotary compressor comprising a casing having a cupped shaped member closed at the open end by a substantially flat closure member, a shaft journaled for rotation in said casing, eccentrics disposed on said shaft at substantially 180° to each other, a pair of cylinders mounted in said casing eccentric to said shaft and secured together at substantially right angles to each other, pistons provided in each of said cylinders and disposed on the shaft for reciprocation by said eccentrics, passages disposed in the wall of each of said cylinders for inlet and outlet of fluid, and a collector plate disposed at each end of the casing to close the discharge passage in each said cylinder during the compression cycle thereof and to open the same for discharge thereafter, one of said collector plates being floatingly supported on the casing and biased against its respective cylinder to effect a constant seal of the collector plates against the rotary cylinders.

7. In a compressor of the class described having a pair of angularly disposed cylinders secured together and mounted for rotation eccentric to a shaft passing transversely therethrough, a pair of opposed collector plates spring biased toward each other and between which said cylinders rotate with a side wall of each cylinder engaging the face of a collector plate, and inlet and discharge ports in the cylinder walls adapted to be closed by said collector plates during the compression cycle of the respective cylinders and to register with passages in the collector plates to provide for the control of fluid discharge from the ends of the cylinders.

8. In a compressor of the class described having a pair of angularly disposed cylinders secured together and mounted for rotation eccentric to a shaft passing transversely therethrough, a pair of opposed collector plates facing toward each other and between which said cylinders rotate with a side wall of each cylinder engaging the face of a collector plate, and inlet and discharge ports in the cylinder walls adapted to be closed by said collector plates during the compression cycle of the respective cylinders and to register with passages in the collector plates to provide for the control of fluid discharge from the ends of the cylinders.

9. In a compressor of the class described having a pair of angularly disposed cylinders secured together and mounted for rotation eccentric to a shaft passing transversely therethrough, a pair of opposed collector plates facing toward each other and between which said cylinders rotate with a side wall of each cylinder engaging the face of a collector plate, inlet ports in said cylinder walls adapted to be controlled by pistons in the cylinders, and discharge ports in said cylinder walls adapted to be closed by said collector plates and to register with passages in the collector plates to provide for the control of fluid

discharge from the ends of the cylinders as the latter rotate.

10. In a compressor of the class described, a cylinder, a collector plate against which one side wall of the cylinder rotates, said cylinder side wall having an outer port disposed to be closed by the collector plate during the compression portion of the compressor cycle, said collector plate having a port for transmitting compressed fluid discharged through said cylinder port during the discharge portion of the compressor cycle, and said collector plate uncovering said cylinder port to provide for inlet of fluid to the cylinder during the intake portion of the compressor cycle.

15. In a compressor of the class described, a cylinder, a collector plate against which one side wall of the cylinder rotates, said cylinder side wall having an outer port disposed to be closed by the collector plate during the compression portion of the compressor cycle, said collector plate having a port for transmitting compressed fluid discharged through said cylinder port during the discharge portion of the compressor cycle, said collector plate uncovering said cylinder port to provide for inlet of fluid to the cylinder during the intake portion of the compressor cycle, and an auxiliary intake port for said cylinder adapted to be opened and cut off by a reciprocating piston in the cylinder.

20. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, and an outlet port in said cylinder disposed to be opened at predetermined cycles in response to rotation of said cylinder for discharge of compressed fluid.

25. In a compressor of the class described, a cylinder, bearings for rotatably supporting said cylinder on a transverse axis, a piston in said cylinder operative to compress fluid therein, a rotary shaft extending eccentrically through one of said bearings and supporting said piston to operate the same, an inlet port in the side of said cylinder adapted to be covered and uncovered by the piston during operation thereof, a passage through one of said bearings for conducting fluid to said inlet port, and an outlet port in said cylinder disposed to be opened at predetermined cycles in response to rotation of said cylinder for discharge of compressed fluid.

30. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

35. In a compressor of the class described, a cylinder, bearings for rotatably supporting said cylinder on a transverse axis, a piston in said cylinder operative to compress fluid therein, a rotary shaft extending eccentrically through one of said bearings and supporting said piston to operate the same, an inlet port in the side of said cylinder adapted to be covered and uncovered by the piston during operation thereof, a passage through one of said bearings for conducting fluid to said inlet port, and an outlet port in said cylinder disposed to be opened at predetermined cycles in response to rotation of said cylinder for discharge of compressed fluid.

40. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

45. In a compressor of the class described, a cylinder, bearings for rotatably supporting said cylinder on a transverse axis, a piston in said cylinder operative to compress fluid therein, a rotary shaft extending eccentrically through one of said bearings and supporting said piston to operate the same, an inlet port in the side of said cylinder adapted to be covered and uncovered by the piston during operation thereof, a passage through one of said bearings for conducting fluid to said inlet port, and an outlet port in said cylinder disposed to be opened at predetermined cycles in response to rotation of said cylinder for discharge of compressed fluid.

50. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

55. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

60. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

65. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

70. In a compressor of the class described, a cylinder, bearings for rotatably supporting said cylinder on a transverse axis, a rotary shaft extending through and eccentrically of said bearings, a piston in said cylinder, an eccentric on said shaft for operating said piston and for rotating said cylinder on its bearings, an inlet port in the side of the cylinder adapted to be covered and uncovered by the piston in said cylinder, a passage through one of said bearings for conducting fluid to said inlet port, and an outlet port in said cylinder disposed to be opened at predetermined cycles in response to rotation of said cylinder for discharge of compressed fluid.

SVEN MALKE.
